Primary Examiner — Keith J Wilson(74) *Attorney, Agent, or Firm* — BUCHANAN,
INGERSOLL & ROONEY PC(57) **CLAIM**

The ornamental design for a nozzle unit, as shown and described.

DESCRIPTION

FIG. 1 is a perspective view of a nozzle unit showing my new design;

FIG. 2 is a perspective view thereof;

FIG. 3 is a top view thereof;

FIG. 4 is a front side view thereof;

FIG. 5 is a left view thereof;

FIG. 6 is a right view thereof;

FIG. 7 is a back view thereof;

FIG. 8 is a bottom view thereof; and,

FIG. 9 is a sectional view thereof.
